UNITED STATES PATENT OFFICE.

JOSEPH A. KREEGER, OF LEES SUMMIT, MISSOURI.

ICE-CUTTER.

1,106,225.

Specification of Letters Patent.

Patented Aug. 4, 1914.

Application filed June 6, 1911, Serial No. 631,549. Renewed November 10, 1913. Serial No. 800,228.

To all whom it may concern:

Be it known that I, JOSEPH A. KREEGER, a citizen of the United States, residing at Lees Summit, in the county of Jackson, State of Missouri, have invented certain new and useful Improvements in Ice-Cutters; and I do hereby declare the following to be a full, clear, and exact description of the invention, such as will enable others skilled in the art 10 to which it appertains to make and use the same.

This invention relates to ice saws and has for an object to provide a motor driven ice saw which will be simple, strong and durable 15 and will be so constructed as to permit of the saw blade being rocked out of the cut more comfortably, with less manual exertion than usual, and without danger of the saw binding or becoming snapped off when being withdrawn from the cut.

With the above object in view the invention consists in certain novel details of construction and combination of parts herein-after fully described and claimed, it being 25 understood that various modifications may be made in the minor details of construction within the scope of the appended claim.

In the accompanying drawing forming part of this specification: Figure 1 is a side elevation of a saw with the blade in operative position. Fig. 2 is a plan view of the saw. Fig. 3 is a side elevation of the saw blade elevated. Fig. 4 is a cross sectional view taken on the line 4—4 Fig. 2. Fig. 5 is a front elevation of the saw.

Referring now to the drawing in which like characters of reference designate similar parts, 10 designates side rails which are connected by cross struts 11, and in the side rails 40 are journaled the end portions of a rear axle 12 upon the opposite ends of which are journaled spur wheels 13 which penetrate the ice and permit of the frame above described being manually pushed over the ice through 45 the instrumentality of a pair of incline handles 14 which are connected to the side rails adjacent to the rear ends of the latter.

Journalized in suitable bearings 14' arranged on the forward end portions of the 50 side rails is a shaft 15, which is equipped with a gear 16 over which and a gear 17 of a gas engine 18 mounted upon the struts 11 a link chain 19 is trained. A second gear 20 is fixed to the shaft and drives the hereinafter described saw blade.

The saw rock frame comprises a pair of

substantially L-shaped side bars 21, provided with suitable journal boxes 22 at their elbows for loosely receiving the shaft 15. The side bars are held in rigid relation 60 through the instrumentality of a rod 23 which connects the outer ends of one pair of the side bar legs and shaft 24 which connects the outer ends of the other pair of the side bar legs, this latter shaft carrying a 65 gear 25 over which and the above mentioned gear 20, a link chain 26 is trained. A circular saw blade 27 is fixed to the shaft. One end of the rod 23 projects considerably 70 beyond one of the side bars and is terminally equipped with a draw link 28 which extends rearwardly along the side rail 10 and is connected to a handle lever 29 which rocks upon a notched segment 30 carried on one of the handle bars 14 within convenient 75 reach of the operator.

In operation the handle lever is shoved forward and through the instrumentality of the draw link the L-shaped saw frame is rocked forwardly, it being understood that 80 the engine has been already started causing the saw to revolve at a high rate of speed. The weight of the saw will cause the free end of the angular frame to gravitate and thus the saw feeds down into the cut, the 85 angular frame rocking freely on its shaft 15 during this gravitating movement of the saw. When a cut of the desired length has been made, the handle lever is pulled rearwardly thereby rocking the angular frame on its pivot and lifting the saw bodily 90 out of the cut. For guiding the saw in making a cut, a gage wheel 31 is equipped with a shaft 32 which is pivotally connected to a bracket 33 arranged on the rear strut 95 11, a hook 34 being arranged on this strut and rocking down upon this shaft for holding the gage wheel in operative position. Upon release of this hook the shaft may be 100 swung to the opposite side of the saw for disposing the gage wheel upon this side of the saw, when a similar hook 35 may be rocked down upon the shaft for holding the gage wheel in its adjusted position.

What is claimed is:—

An ice cutting machine including a wheeled frame, a motor thereon, a shaft arranged transversely across the forward end of said frame and operatively connected to said motor, a gear on said shaft, a rock frame projecting forwardly beyond said wheeled frame comprising spaced L-shaped

bars journaled at their elbows for rotation on said shaft, said bars being held in rigid spaced relation through the instrumentality of a rod connecting the upstanding legs of said bars and a revolvable shaft connecting the forwardly extending legs of said bars, a gear on the last named shaft, an endless connector trained over both of the above named gears, a circular saw fixed on the rock frame to shaft last named, a draw link on said rod

for rocking said frame, means connected to said link for locking said rocking frame stationary, and means connected to said draw link for actuating said rocking frame.

In testimony whereof, I affix my signature, in presence of two witnesses.

JOSEPH A. KREEGER.
